UNITED STATES PATENT OFFICE

SAMUEL OLSON, OF OAK PARK, ILLINOIS, ASSIGNOR TO SAMUEL OLSON & COMPANY, INC., OF CHICAGO, ILLINOIS, A CORPORATION OF ILLINOIS

SELECTIVE UNLOADER MECHANISM FOR ELEVATORS

Original application filed April 11, 1930, Serial No. 443,305. Divided and this application filed June 2, 1931. Serial No. 541,595.

The present invention relates to conveyors, and more particularly to conveyors of the vertically traveling type which employ endless or continuous belts arranged with suitably spaced load carriers. The main object of this invention is to provide improved means for automatically discharging the loads of certain carriers at any one of a plurality of discharge stations arranged along 10 the "down-run" of the conveyor. Another object resides in the provision of selectively adjustable means on the carrier for effecting discharge of the load at a predetermined station along the "down-run" of the conveyor. 15 A further object of this invention resides in the provision of mechanically operated discharge mechanisms adjacent each of a plurality of stations arranged along the down-run of the conveyor, each of said mechanisms including a swinging member normally arranged for closing the effective discharge opening at the respective stations, and means associated with each member adapted to be selectively actuated by means on a carrier 20 for causing said member to be swung into the path of a carrier for intercepting a load and discharging it at said selected station. The invention consists in certain features and elements of construction, in combination, as 25 herein shown and described and as indicated by the claims.

In the drawing:

Figure 1 is a sectional elevation of a vertical conveyor embodying the present invention; taken substantially as indicated at line, 25 1-1, on Figure 2.

Figure 2 is a horizontal transverse section through the conveyor taken substantially as indicated at line, 2-2, on Figure 1.

Figure 3 is a vertical section taken at line, 30 3-3, on Figure 1.

Figures 4 and 5 are enlarged plan and elevational views of my improved form of carrier arm used in connection with the present 35 invention.

Figure 6 is an enlarged fragmentary detail view looking down upon the detent mechanism and taken substantially as indicated at line, 6-6, on Figure 1.

The present invention is a division of my

co-pending application Serial No. 443,305 filed April 11, 1930.

Referring now in detail to the drawing, the vertical conveyor embodying this invention includes one or more endless belts or chains 55 indicated generally at 10, arranged for traveling over head wheels, 11, and foot wheels not shown. The continuous belts which are herein shown as two in number are arranged as a pair and provided with load carriers indicated at 12, spaced at suitable intervals along the belts. These load carriers include a pair of transversely spaced end members, 13 and a plurality of intermediate members, 14. These fingers are arranged to project in substantially the same plane as shown in horizontal direction, forming a fingered tray, the outer ends of which are free and the inner ends of which are rigidly secured to a rock 60 shaft, 15, journaled in the flexible belts. The 65 end members, 13, of the carriers are provided with a pair of rearwardly extending legs, 16, diverging outwardly with respect to each other and having journaled at their ends rollers, 18, which are guided and confined between the vertical legs of a pair of upwardly extending structural members, 19, which form the guideways and insure movement of the carriers in a true path, for maintaining 70 said carriers in substantially horizontal relation for supporting the load. As will be apparent from the drawing, the construction of the carrier is such that it is reversible so that it presents a substantially similar load 75 supporting surface on either the "down-run" 80 side or the "up-run" side of the conveyor.

A plurality of discharge stations indicated generally at A are arranged along the "down-run" side of the vertical conveyor adjacent its path of travel and which may be understood to correspond to floor levels in a building. The vertical walls adjacent each of these stations is formed with a vertical opening, B, for convenient access to the conveyor. To prevent possible injury to attendants it is preferable to protect the openings at the respective stations when these stations are not serving to receive or discharge loads. For this purpose there is mounted in each of the openings 90 for swinging about a hinge axis of a rock 95 100

shaft indicated at 21, a grille, 22, which when in vertical position substantially occupies the space of the opening. This grille member is adapted to serve as a load-intercepting platform and is arranged to be swung about its axis which as shown is adjacent the lower end thereof so that said grille member may be projected into the path of travel of the load carriers, 12, forming an outwardly and downwardly inclined surface for skidding the loads off of the carriers as they travel in a downward direction. As may be seen in the drawing, this grille member is composed of a plurality of transversely spaced fingers, 23, which are spaced at intervals for inter-membering with the finger members, 13 and 14 of the carrier, as illustrated in Figure 2 so as to permit the carrier to pass through the intercepting platform or grille member 20 and the load carried thereon will thus be engaged by these fingers, 23, and skidded outwardly through the opening, B. To assist in discharging the loads I preferably provide an extension indicated at C, which aligns 25 with the surface of the inter-membering platform or grille member when it is disposed in operative position as seen at the upper station in Figure 1. To selectively discharge a load at a predetermined station along the 30 "down-run" of the conveyor there is provided at the respective stations suitable mechanism which is adapted to be actuated by means on the carrier, it being understood that said means on the carrier may be so located 35 as to operate the mechanism at a certain predetermined discharge station.

The discharge mechanisms at the respective stations each include an operating arm, 25, pivotally mounted at 26 to the wall of the 40 elevator shaft with its camming or tail portion, 27, projecting adjacent the path of travel of the carriers and arranged to be engaged by a projection, 28, carried by the adjacent outer member, 13, of the carrier. Connected to the opposite end of the operating arm, 25, is an upwardly extending link, 30, whose lower end is pivotally connected to a crank arm, 31, which is rigidly connected to the grille or intercepting platform, 22, as seen 45 in Figure 1. A spring, 32, encompasses the lower end of the link, 30, and reacts at one end against a fixed stop, 33, secured to the vertical wall and at the other end against a stop shoulder, 30^a, of said link for normally holding the operating arm, 25, in operative 50 position, and the grille, 22, disposed in vertical relation for effectively closing the opening, B. It will be apparent that electrical means may be substituted for the projection 55 on the carrier and cooperating linkage above described, for shifting the load-intercepting platform into operative position.

It may be understood that the camming 60 surface or tail portions, 27, of the operating arms are dimensioned so as to be engaged by a

projection located in a position of adjustment for actuating the discharge mechanism at a predetermined station. To further insure against possible difficulty especially where the carriers have a comparatively short horizontal extension and where it is desired to have a substantial number of discharge stations. In such instances it may be understood that the operating arms of the operating mechanisms provided at successive lower discharge stations are so designed that their camming or tail portions, 27, extend successively farther inwardly than the camming or tail portions of the arms located at the station above. By this arrangement I insure that the projection located in a definite position on the carrier will cause actuation of the arm only at a certain discharge station.

When the projection, 28, on the carrier engages the cam portion of the operating arm, 25, and rocks it about its pivot against the reaction of the spring, 32, swinging the grille or intercepting platform to the inclined position as seen in Figure 1 in the path of travel of the load carrier, a laterally extending pin, 34, which is carried by an arm, 35, which is rigid with the arm, 31, on the grille, is engaged by a latch or detent, 36, and the parts are yieldingly held in such position by a spring member, 37, engaging the lower end 95 of the latch member, 36, as seen in the drawing.

To obtain proper selectivity for operating the discharge mechanism at a desired station I have devised an improved construction which facilitates the locating of the actuating projection on the carrier and prevents it being inadvertently displaced. This improved arrangement consists in forming the end members, 13, of the carriers adjacent the 100 control arms with longitudinally extending slots, 39, and the outer surface surrounding the slot is formed with a series of offsets in the nature of inclined projections, 40, which serve as seats for a co-operatively formed 105 wedge-like washer, 41, which carries the projection, 28. The projection is formed with a stem portion which extends through the slot in the end member of the carrier and is encompassed by a coil spring, 42, which serves 110 to yieldingly hold the wedge member, 41, in position against the tapered seat formed by one of the projections, 40. Thus by merely compressing the spring so that the wedge-like portion, 41, may be raised above the inclined seats, 40, the washer, 41, together with its projection, 28, may be readily shifted toward or away from the axis of the carrier to any other desired position of adjustment 115 which will correspond to a position for actuating a certain control or operating arm, 25, at a predetermined discharge station.

It will be understood that the lug projection or tail piece, 38, of the latch member, 36, will be located at different positions at 130

- the respective stations so as to be engaged only by a properly located projection, 28, on a carrier which serves to actuate the operating arm, 25, at a corresponding station. 5 It will be manifest that after the projection on the carrier has actuated the operating arm, 25, at a selected station as the carrier approaches the station, thereby shifting the intercepting platform or skid, 22, (normally 10 the grille for closing the opening, B) to an inclined position in the path of travel of loads on the carrier and the continued downward travel of the carrier will result in engagement of the load with the skid for dis- 15 charging said load at the corresponding station, and after the carrier passes beyond the intercepting platform the projection, 28, on the carrier will engage the tail portion, 38, of the latch member and rock it about its 20 hinge connection, 38^a, so as to release the pin, 34, rigidly associated with the inter-membering platform and thereby permit said platform or grille, together with the operating linkage to be returned to original 25 inoperative position under the control of the coil spring, 32. As will be noted in the drawing the discharge mechanisms at the respective stations are arranged for co-operation with one side of the carrier, although 30 if desired the mechanism could be so arranged as to operate simultaneously by engagement with both sides of the carrier. The side of the carrier not employed for discharge mechanisms on the "down-run" of 35 the conveyor may be employed for selectively controlling discharge mechanisms on the "up-run" of the conveyor, such as disclosed in my co-pending above referred to application. 40 Although I have shown and described a preferred embodiment of the present invention, it will be understood that it is capable of modification and rearrangement of the parts and that substitute or equivalent mechanisms and devices may be embodied therein 45 without departing from the spirit and scope thereof. I do not therefore wish to be understood as limiting myself to the construction herein shown and described, except as 50 indicated in the appended claims.

I claim:—

1. In combination with a vertically traveling conveyor having a continuous belt and driving means therefor, a load carrier extending laterally and substantially horizontally from said belt and provided with a plurality of transversely spaced load supporting members, mechanically operated load discharging mechanism located adjacent each of a plurality of stations arranged along the down-run of the belt, and selectively adjustable means on the carrier for mechanically actuating the load-discharging mechanism at any predetermined station for effecting discharge of the load thereat, each of

said mechanisms including a load-intercepting platform mounted for swinging about a horizontal axis and means holding it normally out of load-intercepting position, said platform being adapted to be tilted into the path of travel of a carrier for receiving and discharging the load, and automatically operating means independent of the platform tilting means for releasably locking the platform in load-intercepting position. 70

2. In combination with a vertically traveling conveyor having a continuous belt and driving means therefor, a load carrier extending laterally from said belt and provided with transversely spaced supporting members, load discharging mechanism located adjacent each of a plurality of stations arranged along the down-run of the belt, each of said mechanisms including an operating arm and a load-intercepting platform pivotally mounted for tilting into the path of travel of the carrier for receiving the load therefrom, and means on the carrier including a laterally adjustable projection for selectively engaging an arm of the mechanism at a predetermined station for shifting said platform into operative relation, said mechanisms each including a detent associated with the platform for engaging and temporarily holding said platform in such position during discharge of the load, said detent having an arm adapted to be engaged by the projection on the carrier after it has discharged its load for automatically releasing the detent and permitting said platform 100 to be moved out of the path of travel of the carrier and returned to inoperative position. 90

3. In the construction defined in claim 2, yielding means tending to return said platform to inoperative position after release of 105 the detent.

4. The construction defined in claim 1, said automatic locking means having a part extending for cooperation with means on the carrier and said means cooperating with said 110 part for releasing said locking means in the travel of the carrier beyond unloading position.
